(57) **CLAIM**

The ornamental design for a pull, as shown and described.

DESCRIPTION

In a preferred form, the nature of this product is a pull, such as a drawer pull for grasping when opening a drawer.

FIG. 1 is a left, top, front perspective view of a pull embodying my new design;

FIG. 2 is a front elevational view thereof;

FIG. 3 is a left side elevational view thereof, the right side elevational view thereof being a mirror image of the left side shown;

FIG. 4 is a top plan view thereof, the bottom plan view thereof being a mirror image of the top view shown; and, FIG. 5 is a rear elevational view thereof.

The broken line representations of bar structure in FIG. 1-2 and 4-5 and of openings in FIGS. 5 are for the purpose of illustration only, and form no part of the claimed design.
